United States Patent Office

Des. 188,462
Patented July 26, 1960

188,462

CARD TABLE

Thomas S. Haye, P.O. Box 3663, Rincon Annex,
San Francisco, Calif.

Filed Sept. 29, 1958, Ser. No. 52,802

Term of patent 14 years

(Cl. D33—14)

F i g. 1

F i g. 2

F i g. 3

Figure 1 is a perspective view of a card table, showing my new design.

Figure 2 is a bottom plan view of card table showing the legs removed and mounted in internesting pockets therefor.

Figure 3 is a cross-sectional view of card table taken substantially on the line of 3—3 of Figure 2.

I claim:

The ornamental design for a card table, substantially as shown.
